UNITED STATES PATENT OFFICE.

OVERTON WINSTON, OF MINNEAPOLIS, MINNESOTA.

HEADLIGHT.

1,355,876.

Specification of Letters Patent. Patented Oct. 19, 1920.

Application filed February 26, 1917. Serial No. 150,978.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to headlights and is particularly directed to an improved form of lens and to an improved 15 relative arrangement thereof, in respect to a concave reflector and an electric light bulb within the latter.

The invention is illustrated in the accompanying drawings, wherein like characters 20 indicate like parts throughout the several views. Referring to the drawings:

Figure 1 is a vertical section showing a headlight embodying my invention, and wherein a two-filament light bulb is employed as a means for shifting a light source from the axis of the reflector to a point vertically above said axis;

Fig. 2 is an elevation looking at the inner face of the lens;

Fig. 3 is an enlarged fragmentary section on the line 3—3 of Fig. 2;

Fig. 4 is an enlarged fragmentary view in inner face elevation showing a segmental portion of the lens;

Fig. 5 is a longitudinal section taken approximately on the line 5—5 of Figs. 2 and 4;

Figs. 6, 7, 8, 9 and 10 are fragmentary sections taken on the lines 6—6, 7—7 8—8, 40 9—9 and 10—10 of Fig. 4;

Fig. 9^a is an enlarged section of one of the prismatic sections shown in Fig. 9;

Fig. 11 is a view corresponding to Fig. 1, but showing a headlight having a single filament light bulb and a slightly modified form of lens;

Fig. 12 is an inner face elevation showing the lens illustrated in Fig. 11;

Fig. 13 is an enlarged section on the line 50 13—13 of Fig. 12;

Fig. 14 is an enlarged fragmentary view in inner face elevation showing a segmental portion of the lens illustrated in Fig. 13;

Fig. 15 is a section on the line 15—15 of 55 Fig. 14;

Figs. 16, 17, 18, 19 and 20 are sections

taken, respectively, on the lines 16—16, 17—17, 18—18, 19—19 and 20—20 of Fig. 14; and

Fig. 20^a is an enlarged section of one of 60 the prismatic segments shown in Fig. 20.

Of the parts of the headlight, the numeral 21 indicates the casing, the numeral 22 the clamping ring thereof, the numeral 23 the concave reflector, the numeral 24 the electric light bulb, and the numeral 25 the lens. The reflector 23 is preferably a hyperbolic reflector and it is provided with an axial passage through which the shank of the bulb 24 projects and is held by a suitable support. 70 This bulb support, so far as this invention is concerned, may be of any suitable construction, but, as shown, comprises a shank 75 engaging sleeve 26 and a tubular socket body 27 screwed into a flanged hub 28 secured on the back of the reflector.

The bulb shown in Fig. 1 is a two-filament bulb, the one filament having its hot spot at *a* and the other having its hot spot at *b*. The point *a* is at the axis of the reflector and preferably also at the focal center thereof. The point *b* is vertically above the axis of the reflector. By means of a three-lead circuit 29, 30 and 31, which includes a battery 32 and switches 33 and 34, either of the two filaments *a* or *b*, may, at will, be energized and used at the light source of the headlight.

In Fig. 11 the light bulb 16 is provided with a single filament *c*, the hot spot of 90 which is at the axis of the reflector and preferably also at the focal center thereof. This filament is connected to a battery or source of electrical energy 35 by leads 36 in any one of which is a switch 37.

We will now consider the novel construction of the lens, the preferred form of which is illustrated in the drawings and which, described, is as follows, and will first consider the construction shown in Figs. 1 to 100 10, inclusive;

One surface, preferably the inner surface of the lens is formed with radial prismatic segments of peculiar form. These prismatic segments radiate from the center of the lens, or from the axis of the reflector and have their greatest bevel at, or nearest to the rim of the reflector. For example, assume that the bevel surface of the prismatic segment has an angle of 22 degrees at the rim of the reflector, and that in a direction toward the axis of the reflector, this angle progressively 105 110

decreases to zero at the said axis. This, as is obvious, produces the greatest thickness in the segments at points nearest to the rim of the reflector. All of the said segmental 5 prisms, preferably, have an angle of approximately zero at their inner extremities; but the different prismatic segments, in a direction circumferentially of the lens, will vary in their maximum angle. In the preferred 10 arrangement, the maximum angle of the prismatic segments, at their outer extremities, in a direction circumferentially of the lens, increase progressively from the upper vertical line, down to the horizontal 15 radial line and below such horizontal line, have progressively decreasing angles. In Fig. 2, the maximum angle of the prismatic segments, at their outer extremities, are indicated by the small numerals marked adjacent thereto.

As already indicated, the beveled surfaces of the prismatic segments flare, or diverge from the plane of the reflector in opposite directions from the upper vertical line of 25 the lens. This arrangement produces a minimum downward deflection of the more intense rays from the back or inner portion of the reflector, and a maximum downward deflection of the less intense rays from the 30 outer portion of the reflector. The general effect is to produce a material downward deflection of the light beam. This arrangement, when the light source is at *b*, gives a good beam for city street driving.

35 In the modified form of the lens shown in Figs. 11 to 20, inclusive, a considerable portion of the lower part of the lens is left smooth or free from prismatic lens segments, and while the various prismatic segments have beveled surfaces that decrease in angle from the rim radially toward the axis of the lens, the decrease in angle is less rapid than in the previously described construction. For example, the lens segment 40 varying a maximum of 22 degrees at the rim of the lens, would decrease toward an angle of approximately 11 degrees at the axis of the lens. Otherwise stated, the several prismatic segments have decreasing angles from 45 the outer toward the inner portion, varying from the said maximum angle to approximately one-half of that maximum angle.

50 In Fig. 12, the maximum angles of the several segmental prisms at the rim of the lens, are indicated by the small numerals marked adjacent thereto.

The beveled surfaces of the prismatic segments that are on opposite sides of the upper vertical line of the lens, incline or bevel 55 in reverse directions, so that they increase the thickness of the prisms in both directions, circumferentially from the said upper line. This direction of the bevel is important because it causes the rays that leave the 60 face of the lens to be given a material

downward deflection, or, in other words, projection below the radial planes of both the reflected and direct rays. The effect of this is to produce a general downward deflection of the light beam, so that a very 70 much greater part thereof, will reach the ground than with any lens known to me. Moreover, it is the rays of the beams that ordinarily are projected upward and which produce blinding effects, but do not light 75 the road, that are thus most deflected or refracted, and turned downward onto the road. This arrangement also permits a still further improved light effect. Moreover, it is the rays that are most nearly to a horizontal 80 that are given the greatest downward deflection. The exact manner in which the segmental prisms are distributed may be varied but are preferably as illustrated in the drawings and above described in detail. 85

With the two filament light bulb or shifting light source shown in Fig. 1, there will be the above noted downward deflection of the beam when the light source is at point *a*, but this downward deflection will be materially increased when the light source is shifted from *a* to *b*. Hence, the shifting light source, in combination with a lens, such as described, makes possible a light beam of long projection, but with a maximum amount of light on the road and a minimum amount of light above the road. 95

An ideal beam for headlights for city street driving is, as already indicated, produced when the light source is at the vertically offset point *b*. 100

In the use of a headlight with an ordinary reflector adjusted so as to throw approximately the lower half of the light beam upon the ground, which is a quite common 105 arrangement, the lower half of the light beam will be distributed over many hundreds of square feet of road surface, and per unit of surface, the road will be given but a very small percentage of light, as compared 110 with the amount of light thrown upon a vertical object in the road, by the upper half of the light beam. This is a result just reverse from that desired. An ideal arrangement would be one in which there 115 would be at least as much light per unit of surface thrown upon the road as there would upon a vertical object above the road; and such an arrangement, obviously, requires very much the greater part of the light beam to be distributed on the ground and a very minor part of the light beam to be diffused above the road. This ideal result is closely approximated by the use of the improved lens above described, which, 120 as already stated, produces very great downward deflection of the more intense rays of the light beam and diffuses some or a minor part of the less intense light rays above the road. 125

What I claim is:

1. A lens for headlights having a group of prisms beveled in the same general direction, the individual prisms, in themselves, in a direction from the rim of the lens inward, having decreasing angles to the basal surface of the lens.
2. A lens for headlights having a group of prisms beveled in the same general direction, which, among themselves, in a direction circumferentially of the lens, having varying angles to the basal surface of the lens, the individual prisms, in themselves, in a direction inward from the rim of the lens, having decreasing angles to the basal surface of the lens.
3. A lens for headlights having a group of prisms beveled in the same general direction, which prisms, among themselves, in a direction circumferentially from the vertical toward the horizontal diameter of the lens, have progressively increasing angles to the basal surface of the lens, the individual prisms, in themselves, in a direction inward from the rim of the lens, having progressively decreasing angles to the basal surface of the lens.
4. A lens for headlights having a group of prisms beveled in the same general direction, which prisms, among themselves, in a direction circumferentially from the upper toward the lower portion of the lens have progressively increasing angles to the basal surface of the lens, the individual prisms, in themselves, in a direction inward from the rim of the lens, having decreasing angles to the basal surface of the lens.
5. A lens for headlights having two groups of prisms disposed on opposite sides of its vertical diameter, the prisms in the same group being beveled in the same general direction, and the prisms of different groups being beveled in opposite directions, the individual prisms, in themselves, in a direction inward from the rim of the lens, having decreasing angles to the basal surface of the lens.
6. A lens for headlights having two groups of prisms disposed on opposite sides of its vertical diameter, the prisms of the same group being beveled in the same general direction and having, among themselves, in a direction circumferentially of the lens, varying angles to the basal surface of the lens, the individual prisms, in themselves, in a direction inward from the rim of the lens, having decreasing angles to the basal surface of the lens.
- a direction inward from the rim of the lens having varying angles to the basal surface of the lens.
7. A lens for headlights having two groups of diverging prisms disposed on opposite sides of its vertical diameter, the prisms in the same group being beveled in the same general direction and having, among themselves, in a direction circumferentially from the upper toward the lower portion of the lens, progressively increasing bevel to the basal surface of the lens, the individual prisms, in themselves, in a direction inward from the rim of the lens, having progressively increasing angles to the basal surface of the lens.
8. A lens for headlights having radial prismatic segments, the beveled surfaces of the segments of which have maximum angles to the plane of the lens at their outer portions and decreasing angles toward the center of the lens, the said prismatic segments, in directions circumferentially of the lens, having progressively varying maximum angles to the plane of the lens.
9. A lens for headlights having radial prismatic segments, the beveled surfaces of the segments of which have maximum angles to the plane of the lens at their outer portions and decreasing angles toward the center of the lens, the beveled surfaces of the prismatic segments, on opposite sides of the upper vertical line of the lens, diverging from the plane of the lens in opposite directions circumferentially thereof.
10. A lens for headlights having radial prismatic segments, the beveled surfaces of the segments of which have maximum angles to the plane of the lens at their outer portions and decreasing angles toward the center of the lens, the said prismatic segments, in directions circumferentially of the lens, having progressively varying maximum angles to the plane of the lens, the beveled surfaces of the prismatic segments on opposite sides of the upper vertical line of the lens diverging from the plane of the lens in opposite directions circumferentially thereof.

In testimony whereof I affix my signature in presence of two witnesses.

OVERTON WINSTON.
